UNITED STATES PATENT OFFICE.

SØREN OPSAL, OF STAVANGER, NORWAY, ASSIGNOR TO FREDRIK WATTNE, OF STAVANGER, NORWAY.

SEAMING-MACHINE.

No. 904,009.

Specification of Letters Patent.

Patented Nov. 17, 1908.

Application filed December 4, 1906. Serial No. 346,304.

To all whom it may concern:

Be it known that I, SØREN OPSAL, a subject of the King of Norway, residing at Stavanger, Norway, have invented certain new and useful Improvements in Seaming-Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to improvements in seaming machines and particularly to that class of machines, in which the seaming tools are controlled by two cams, the configuration of which is adapted to that of the can to be

20 seamed.

The objects of the invention are to provide means whereby one of said cams holds the seaming tools in contact with the seam, while the other cam serves as a kind of complementary cam to give the tools a steady movement; to provide an improved construction of the controlling rollers, whereby the seaming rollers, as soon as the seaming is finished, are automatically released from 25 their contact with the can whereby the operative period of the machine is, to a certain extent, made independent of the number of rotations.

30 A further object of the invention is to provide an improved construction of holder for the seaming rollers for the purpose of making them easily adjustable.

In the accompanying drawings, Figure 1 is a side elevation; Fig. 2 a front elevation; 35 Fig. 3 a ground plan of a complete machine, embodying my invention; Fig. 4 is a vertical section on a larger scale through the upper portion of the machine; Fig. 5 is an elevation of the same part of the machine 40 seen from the left of Fig. 4; Fig. 6 is a plan view of the controlling mechanism. Figs. 7 and 8 are respectively, a plan, and side view of the controller disks. Figs. 9, 10 and 11 are respectively, a side, end and plan view of 45 one of the seaming rolls and the means for adjustably supporting them, and Fig. 12 is an enlarged detail view of the means for connecting the controller disks to the operating rod.

50 Corresponding and like parts are referred

to in the following description and indicated in the several views of the drawings by the same reference characters.

The frame of the machine comprises a standard 1 mounted on a suitable base A and provided near its lower end with a horizontal arm 2 in the outer end of which is formed a guide for a supporting rod 3. Said rod has on its upper end a head 4 for the reception of the cans to be operated upon and is 60 provided with longitudinal ribs 5 working in grooves in said bearing to prevent rotation. The head is held in the operative position, shown in the drawings, by the following mechanism. A sleeve 6 surrounds the 65 rod, below the bearing 2 and is pivotally connected to two parallel rods 8 which rods are articulated to a rod 9 forming a knee joint 7. The lower end of rod 9 is fulcrumed in a bracket 10 and has a foot lever 13 connected thereto below the fulcrum and levers 8 and 9 are held in a vertical position by a 70 spring 14 connected to the lever 9 and standard A. The rod 3 and sleeve 6 are detachably connected by means of a latch 11 on the 75 end of the rod 3 taking over a flange 12 formed on the sleeve.

From the upper end of standard 1, an arm 1^a projects parallel to the arm 2. In the arm 1^a is fixed a depending tubular shaft 15 the 80 axis of which is in a line with the axis of rod 3. A pulley 16 is rotatably mounted on shaft 15 and rests on a breast bearing 45, Fig. 4, and held against longitudinal movement on the shaft by a nut 47 and lock nut 48. This 85 pulley carries two diametrically oppositely positioned sleeves 17 and 17^a in which are journaled spindles 18, 19 respectively and on the ends of these spindles are keyed curved arms 20, 21 and 22, 23 respectively. The 90 arms 20 and 21 on opposite ends of shaft 18 and the arms 22 and 23 on opposite ends of shaft 19 point in opposite directions to each other as shown in Fig. 6 and carry controlling 95 rollers 24, 25 and 26, 27 respectively. On each of the arms 21 and 23 is also journaled a seaming roller 28, 29 respectively. Each controlling roller has a bevel face 30 situated in a different horizontal plane and corresponding with similar faces 31 of two 100 non-rotating controller disks 32, 33. One form of controlling disk is shown in plan in Fig. 7 but these disks may be of any configuration to conform to the shape of the can 105 to be seamed. Each controlling roller 25

110

and 27 has an additional bevel face 34 inclined in the opposite direction to that of the bevel faces 30.

The controller disks surround the shaft 5 and are movable longitudinally thereof into and out of contact with the bevel faces of the controlling rollers by means of a rod 35, slidably mounted in the tubular shaft 15. The means here shown for connecting the 10 disks with the rod 35 consists of lugs 36, 37 which project from said rod through slots 38 in the shaft 15 and rings 39, 40 which surround said shaft and slide thereon are secured to the lugs by screws, said rings being 15 provided with peripheral threads onto which the disks are screwed. Guide rods 41 are secured to disk 32 and extending above and below the same slide through plates 42 and 43 fixed on the shaft 15 on each side of said 20 disk. Disk 33 slides on stationary guide rods 44 which have their upper ends threaded in the fixed breast-bearing 45 of the pulley; the lower ends of said rods supporting a forming head 46 on the end of shaft 15. 25 The rod 35 projects through the top of shaft 15 and is hinged to one end of a lever 49, fulcrumed on a bearing 50 on the arm 1^a of the standard 1. A hand lever 51 is fixed to the lever 49 at the fulcrum point and on 30 the free end of the latter lever is mounted a socketed member 52 designed to take over the upper end of a stem 54, slidably mounted in a bracket 53 on the standard 1 and normally held in a raised position by a spring 35 55. The stem extends through a slot (not shown) in the standard 1 and its lower end normally rests against the operating end of the latch 11 so that when the stem is depressed, as hereinafter described, the hook of 40 the latch will release the sleeve 6 and allow the rod 3 to drop.

An operating shaft is shown journaled in the base A and standard a and carries a driving pulley 63 and a fixed and loose pulley 45 64, 65 respectively. A driving belt (not shown) is passed from either of the latter pulleys over guide rollers 66 to pulley 16 and may be shifted by a rod 57, carrying a belt guide 56, said rod being slidably mounted 50 in consoles 58. This rod 57 is connected by a pin 59 to one end of a lever 61 which is pivoted at 60 to the base and has at its opposite end a foot plate 62. The bearings for the rod 57 in said consoles are sufficiently 55 large to permit the slight lateral movement of said rod which is imparted thereto by the arc described by the movement of lever 61.

To the arms 21 and 23 are secured holders 71 in which forks 72 that carry rollers 28 60 and 29 are mounted. These holders have parallel jaws 71^a, 71^b, between which is mounted a sleeve 73 provided with a threaded shank 74 which passes through the holder. The shanks of the forks extend through the 65 jaws and sleeve, and by moving said shanks

longitudinally or axially rotating them a proper adjustment of the seaming roller may be attained. When properly adjusted a nut 75 on the end of the threaded shank will draw the sleeve 73 out of alignment with the 70 jaws 71^a, thus clamping the fork-shank in its adjusted position.

The machine operates in the following manner. The can to be seamed is placed on head 4, footlever 13 is pressed down; and 75 bars 8, 9 will thereby form a knee at 7, and the clutch-block 6 pulled down, until latch 11 will catch with lug 12 on the clutch-block 6. Footlever 13 is now released, and the spring 14 will then force bars 8, 9 and rod 3 80 with its head 4 back to the position shown in Fig. 1, in which position the can is retained between the head 46 and head 4. By forcing down the foot plate 62 the belt passes from the loose pulley 65 across to the fixed pulley 85 64, whereby pulley 16 is rendered operative together with the seaming instruments. The seaming operation is now effected by pulling the lever 51 to the right from the position shown in Fig. 1 whereby an upward movement is imparted to controlling disks 32, 33, coincident with the downward movement of the member 52 on the lever 49. The bevel edge 31 of disk 32 will then first bear upon the bevel face 30 of controlling roller 26 95 forcing it outward, whereby seaming roller 29 on arm 23 comes into contact with the can by means of arm 22, shaft 19 and arm 23. While this goes on the bevel face 30 of controlling roller 27 is riding upon the bevel 100 edge 31 of controlling disk 33, thereby steadyng the seaming instruments. When the bevel edge 31 of plate 32 has passed the bevel face of roller 26, it bears upon the bevel portion of controlling roller 24, pressing it outward, and seaming roller 28 is 105 brought into contact with the can in the same way as already indicated for seaming roller 29. As soon as the edge of disk 32 has passed the highest edge of the bevel face 110 30 of roller 24, the edge of disk 33 first bears upon the little bevel face 34 of roller 27, thereby releasing seaming roller 29 from its contact with the can, and then it bears upon the bevel face 34 of controlling roller 25, 115 releasing seaming roller 28 from contact with the can; immediately afterwards the socket 52 on lever 49 strikes against the upper end of stem 54 pressing it downward, thereby releasing latch 11 from lug 12 on 120 clutch part 6 and permitting bar 3, head 4 and the can to come down. Coincident here-with footplate 62 is raised by the toe of the operator which moves rod 57 from right to left, shifting the belt from the fixed pulley 125 64 to loose pulley 65 and lever 51 is brought back into its original position by the hand of the operator. When the next can is placed on the head 4, now in its lowered position, the foot lever 13 is depressed, lower- 130

ing the sleeve 6 until it is engaged by the latch 11. As soon as the operator removes his foot from lever 13 levers 8 and 9 are returned to their vertical position by the action of the spring 14, and the head 4 with the can is raised into seaming position. Lever 62 is again depressed to shift the belt from the loose to the fast pulley, and as soon as the operator begins to pull the lever 51 toward the right, from the position shown in Fig. 1, the seaming operation is resumed.

I claim:—

1. In a seaming machine the combination with a can-support and seaming members 15 rotatable around the latter, of two controlling disks, two controlling rollers connected with each seaming member in different planes one of said rollers adapted to be actuated by one of said disks and the other 20 roller moved by the actuation of the first roller into contact with the other disk for the purpose set forth.

2. In a seaming machine, the combination with a can-support and seaming rollers 25 rotatable around the latter, of a pair of controlling rollers situated in different planes connected with each seaming roller, a pair of controlling disks, one of which is adapted to successively engage one roller of each pair of 30 controlling rollers and the other disk to be engaged by the other roller of each pair of controlling rollers.

3. In a seaming machine the combination with a can-support and a pair of seaming 35 rollers rotatable around the latter, of a pair of controlling rollers mounted in different planes connected with one of said seaming rollers, a pair of controlling rollers mounted in different planes connected to the other 40 seaming roller, and a pair of controlling disks, one of which is adapted to successively engage one roller of each pair of controlling rollers and the other to be successively engaged by the other roller of each pair.

4. In a seaming machine, the combination 45 with a can-support, seaming rollers rotatable around the latter, and a pair of controlling

disks, of a pair of connected controlling rollers mounted in different planes connected with each seaming roller one of the controlling rollers of each pair adapted to be operated by one of the disks to move its seaming roller into contact with the can to be seamed and the other controlling roller of each pair adapted to be operated by the other disk to move its seaming roller away from said can.

5. In a seaming machine, the combination with a can-support, a supporting shaft, a pulley journaled on said shaft, and controller shafts carried by the pulley, of an arm on each end of the controller shafts projecting in opposite directions, a seaming roll connected with each controller shaft, a roller on the free end of each arm having cam faces 65 in different planes and disks slidably mounted on the supporting shaft to successively engage the cam faces on the rollers.

6. In a seaming machine, in combination with the seaming rollers, a rod movable to 70 and from the same to support the cans, a support in which the rod slides, a clutch on the rod to connect the rod and support, a controlling mechanism for the seaming rollers, and means to automatically release 75 the clutch at the end of the seaming operation.

7. In a seaming machine, in combination, a plurality of supporting arms connected in pairs, controlling rollers carried by the arms 80 means to actuate the rollers, a holder mounted on one arm of each pair of supporting arms, a fork axially rotatable and longitudinally movable in each holder, a crimping roller in each fork and means to clamp the 85 forks in the holder.

In testimony that I claim the foregoing as my invention, I have signed my name in presence of two subscribing witnesses.

SÖREN OPSAL.
